COMBINED EXPANSIBLE WATCH BAND AND
WATCHCASE

Kurt Speck, Palisades Park, N. J., assignor to
Jacques Kreisler Manufacturing Corporation,
North Bergen, N. J., a corporation of New Jersey

Application May 17, 1951, Serial No. 15,216

Term of patent 7 years

(Cl. D45—4)

To all whom it may concern:

Be it known that I, Kurt Speck, a citizen of the United States of America, residing at Palisades Park, county of Bergen, and State of New Jersey, have invented a new, original, and ornamental Design for a Combined Expansile Watch Band and Watch Case, of which the following is a specification, reference being had to the accompanying drawing, forming part thereof.

In the drawing:

Fig. 1 is a developed plan view of a combined expansile watch band and watch case;

Fig. 2 is a side elevational view thereof as illustrated in Fig. 1;

Figs. 3 and 4 are enlarged perspective and side elevational views, respectively, of one of the top links.

The dominant feature of the design resides in the top links of the expansile band portion shown in full lines on the drawing. The band portion is continuous as indicated in Figs. 1 and 2.

I claim:

The ornamental design for a combined expansile watch band and watchcase, substantially as shown and described.
